RENÉ H. NÉRAT, OF NEW YORK, N. Y.

NON-REFILLABLE BOTTLE.

1,191,026.

Specification of Letters Patent. Patented July 11, 1916.

Application filed October 1, 1915. Serial No. 53,628.

To all whom it may concern:

Be it known that I, RENÉ H. NÉRAT, a citizen of the United States, residing at New York, in the county of New York and 5 State of New York, have invented certain new and useful Improvements in Non-Refillable Bottles; and I do hereby declare the following to be a full, clear, and exact 10 description of the invention, such as will enable others skilled in the art to which it appertains to make and use the same.

This invention relates to bottles and jars, and the object of same is to produce a new valve and new coacting parts including a 15 guard which, placed in and forming part of the neck of bottles and jars, renders them non-refillable. This object is carried out by constructing the bottle neck in a manner hereinafter more fully described and claimed 20 and as shown in the drawings wherein:

Figure 1 is a central vertical sectional view through a bottle neck with the bottle inverted and in the act of pouring out its contents, and Fig. 2 is a similar view with 25 the bottle upright, showing how the valve has dropped onto its seat to prevent the refilling of the bottle. Fig. 3 is an enlarged perspective detail of the valve, partly broken away. Figs. 4 and 5 are sectional views of 30 slightly different forms of the valve; and Fig. 6 is an enlarged perspective detail of the seat, partly in section.

In the drawings I have used the letter N to designate the bottle neck, no matter 35 whether the same be integral with the bottle body B or not, and I will refer to it by the term "neck" throughout the specification although it is quite possible that this tubular element within which is mounted my im- 40 proved valve might be formed separate from the neck and attached integrally or otherwise thereto at a later time. If the bottle be of glass the neck will be of the same material, but if this tubular element be sepa- 45 rate from the neck it may be of glass or any other material desired.

Coming now to the gist of the invention, the upper end of the neck is preferably closed as at 1 excepting for a central opening 2 somewhat smaller than the neck so as 50 to produce a reduced mouth for the same, this mouth being intended to be closed by a cork or other commercial closure while the bottle is in storage or transit. Immediately 55 beneath the mouth is a guard, herein shown as a disk 3 somewhat larger than the open-

ing 2 and having a raised peripheral bead 4 which is spaced longitudinally from the inner side of the upper end 1 as at 5 and is spaced radially from the interior of the neck 60 as at 6, so that liquid flowing out of or in through the mouth must pass over the bead 4 and around the edge of the guard.

The neck N is illustrated as composed of two concentric tubular elements with an interposed spiral rib, and in manufacture these may all be made integral or may be made in separate parts and subsequently united in a waterproof manner. The outer element or shell 10 extends throughout the 65 entire length of the neck and unites with the edge of the upper end piece 1. The inner element or tube 11 is concentric with and spaced slightly from the shell than which it is somewhat smaller in both diameter and 70 length so that its outer end stands some distance from the end plate 1 and its inner 75 end 12 stands some distance from a shoulder 13 which projects inward from the shell 10 and coacts with another shoulder 14 to receive the edge of the seat as described below. In other words, the tube is about five millimeters shorter than the shell at each end. Between these elements is disposed a spiral 80 rib 15 which makes about one complete convolution within the length of the tube 11, thereby producing a spiral channel 16 between the convolutions which has its inlet 85 end 17 communicating with the interior 18 of the neck past the inner end 12 of the tube 11 at one side, and its outlet end 19 communicating with the space 6 around the edge 90 of the guard at the other side of the neck. From the construction thus far described it will be clear that liquid passing either in or 95 out, if it could not pass through the bore of the tube 11, would have to follow a spiral course throughout the length of the channel 16 and flow about once around the neck in its passage.

Clamped between or in any way mounted in the space between the shoulders 13 and 100 14 is a valve seat best shown in detail in Fig. 6. The same comprises a tubular body 20 in the shape of a truncated cone, and an 105 outstanding flange 21 projecting from the larger lower end of the body into the space between said shoulders, wherein it is shown in Fig. 2 as being held between suitable rings of packing 22. The smaller upper end 110 23 of the body is of somewhat less circumference than the interior of the tube 11.

The valve best seen in Fig. 3 comprises a cylindrical body or shell 30 open at its upper end 33 and closed at its lower end, and by preference I would make this valve of very thin metal and quite light, the circumference of its body being such that it will fit closely and yet slidably within the bore of the tube 11. At the lower end of the body the metal of which it is composed is bent abruptly inward in an acute angle 34, then carried obliquely upward in an inclined wall formed in the shape of a truncated cone 35 whose smaller upper end is closed as at 36. In the form of the valve shown in Figs. 1, 2 and 3, this closure is an annular band, and from its inner edge depends a short section of cylinder 37 extending downward to a point 38 about opposite the vertex of the angle 34, beneath which it is closed by a cone-shaped bottom 39. In Fig. 4 the structure of the valve is the same excepting that the cone-shaped bottom 39 is replaced by a flat bottom 40. In Fig. 5 the short section 37 of cylinder is omitted, and the upper end of the truncated cone 35 is closed by a flat plate 41. But I consider it important to state that in any case the inclination or pitch of the wall of the cone 35 on its interior is less than that of the exterior of the body 20 of the seat. Attention is here directed to the fact that the seat 20 is of such size and so disposed that its body 20 crosses the path of the shell 30 of the valve, and the result is that when the valve closes upon the seat as seen in Fig. 2, the vertex of its angle 34 strikes the outer face of the body 20 at a point between the upper and lower edges of the latter and close engagement results.

The guard is mounted upon the upper end 40 of the tube 11 in any suitable manner which will permit liquid within the space 6 to flow into the upper end of said tube, for a purpose yet to appear; and by preference I provide the disk 3 with tongues or fingers 43 around its edge which are secured within the upper end of the tube 11 at intervals and in any suitable manner, leaving spaces 46 between them which communicate with the space 6 and making use of their inner extremities as stops to limit the outward movement of the valve. It will be observed from Fig. 2 that when the valve is closed the upper end 33 of its body is spaced from said stops and the vertex of its angle 34 rests on the seat; whereas when the valve is open as seen in Fig. 1 the vertex of its angle is off the seat and its upper end rests on said fingers, its length being such that at this time the spaces 17 and 18 are thrown into communication over the upper end 23 of the seat.

In use, the bottle is filled and probably the neck N will afterward be applied and sealed in place, the mouth 2 is corked or otherwise closed, and the bottle shipped to the consumer. To pour off its liquid, the

cork is removed and the bottle inverted as seen in Fig. 1. The valve now falls away from its seat against the fingers 43 and the spaces 18 and 17 are thrown into communication as just stated, and liquid flowing over the seat at 23 enters the spiral channel 16 and passes around the convolutions thereof to the point 19, whence it flows alongside the guard as at 6, between it and the top plate 1 as at 5, and out the mouth 2. This is the action whether the bottle is completely inverted as shown, or only partially. After using, the bottle is restored to the position shown in Fig. 2, and the valve drops closed onto its seats ready to act again when more liquid is to be poured out.

When now it is attempted to refill the bottle, the advantages of the construction described appear. Whatever the position in which the bottle is held, when liquid is poured or forced into its mouth 2, some of it passes through the spaces 46 between the fingers and gets into the cup-shaped body 30 of the valve. If the device stands upright as seen in Fig. 2 the valve will obviously drop to a closed position by its own weight and the added weight of the liquid therein, and this also is true if the bottle stands inclined. If the bottle should be first inverted and the valve allowed to fall to its open position as seen in Fig. 1, and it is then turned on its side to a horizontal position, it will yet be impossible to refill it, as I will show. Liquid forced into the mouth 2 now strikes the guard and passes around its lower edge to the point 19 where it enters the first convolution of the channel 16 and rises inside the same as the supply is kept up; but in so doing, some of the liquid passes through the space 46 under and behind the guard and into the cup-shaped body 30 of the valve, and rises simultaneously therein.

Manifestly it will be impossible to force liquid into the channel without also forcing it into the valve, and before sufficient liquid has been driven into the channel to cause it to travel around even the first convolution thereof, the weight of the liquid within the valve will slide the latter within the bore of the tube 11 and close it upon its seat. Thereafter, even if it were possible to force the liquid around the several convolutions of the channel, when it came to the point 17 where the innermost convolution opens outside the seat, it would strike the valve (which now rests tightly on the seat) and could not enter the bottle. The guard therefore serves the purpose of causing some of the liquid to be admitted to the valve so as to seat the latter, even though the bottle neck stands horizontal; and in addition the guard serves its customary purpose of preventing the insertion of an instrument to hold the valve open while the bottle is refilled. The conical bot-

tom 39 in the valve shown in Fig. 3 amplifies the amount of liquid it may receive. The flat bottom 40 of Fig. 4 will make it hold less, and the construction of Fig. 5 still less, 5 but probably the body of the valve would in any event hold enough liquid to cause it to act as described.

The present invention is an amplification 10 of the idea disclosed in a prior application by me bearing Serial Number 857,727, filed August 20th, 1914, allowed June 7, 1915, and abandoned January 3, 1916.

What I claim is:

1. In a non-refillable bottle, the combination 15 with a bottle neck whose wall contains a spiral channel opening at its upper and lower ends into the bore of the neck, and a tubular valve seat secured within the lower end of the neck below said channel and made 20 conical on its exterior; of a valve having a hollow cylindrical outer wall of less length than and slidably fitting within the neck, a frusto-conical wall making a sharp angle at its lower edge with said outer wall and 25 extending thence inward and whose sides are of less pitch than the exterior of said seat, and a closure for the top of the frusto-conical wall, for the purpose set forth.

2. In a non-refillable bottle, the combination 30 with a bottle neck whose wall contains channels opening at their ends into the bore of the neck near the extremities of said bore, and an annular valve seat secured within the lower end of said neck and made frusto-35 conical on its exterior; of a valve having a cylindrical hollow outer wall closely and slidably fitting within said neck, a frusto-conical wall rising obliquely from the lower edge thereof, a flat ring adapted to overlie 40 the upper edge of said seat, a cylindrical inner wall depending from the inner edge of said ring, and a bottom closing the lower end of said inner wall.

3. In a non-refillable bottle, the combination 45 with a bottle neck comprising spaced cylinders with ribs between them producing channels opening at their extremities through the inner cylinder near its ends; of an annular valve seat secured within the 50 neck and having a frusto-conical exterior spaced from the inner end of the inner cylinder; and a valve comprising a hollow cylindrical shell slidably fitting within the bore of said inner cylinder, an internal truncated

wall rising in a sharp angle from the lower 55 edge thereof, the apex of said angle adapted to contact with the frusto-conical face of the seat, a ring within the smaller end of said truncated wall, and a closure across the ring.

4. In a non-refillable bottle, the combination 60 with a bottle neck comprising spaced cylinders with ribs between them producing channels opening at their extremities through the inner cylinder near its ends; of an annular valve seat secured within the 65 neck and having a frusto-conical exterior face spaced from the inner end of the inner cylinder; a valve having a cylindrical shell closely and slidably fitting within the inner cylinder, bent at its lower edge into a wall 70 standing at a sharp angle to said shell, the apex of such angle adapted to contact with the face of said seat, and a bottom extending from such wall across the shell, and a guard rigidly mounted between the upper 75 end of said inner cylinder and the mouth of the neck.

5. In a non-refillable bottle, the combination 80 with a bottle neck comprising an outer shell connected at its lower end with the bottle, a tube disposed concentrically within and spaced from and shorter than said shell, spiral ribs uniting these elements and producing spiral channels opening into the bore 85 of the tube at its upper and lower ends, and an annular plate within the upper end of the shell and having a central opening smaller than said bore; of a guard comprising a disk disposed between said plate and tube and spaced from both and having 90 a peripheral bead on its outer face and fingers around its edge projecting into and secured to said tube; an annular seat having a frusto-conical body spaced from the inner 95 end of said tube, and a flange at its larger end secured to the neck; and a valve slidably mounted within the bore of the tube and adapted alternately to rest on the seat and close said opening from the inner convolution, or to rise from said seat and abut at 100 its upper end against said fingers.

In testimony whereof I affix my signature in presence of two witnesses.
